GUIDE SETTING MECHANISM

Robert W. Stewart, Apalachicola, Fla.

Application July 14, 1937, Serial No. 153,667

2 Claims. (Cl. 143—174)

My invention relates to improvements in setting mechanism for straight line rip, or, edging saw guides, and the primary object thereof is to provide a mechanism of simple inexpensive construction for accurately and quickly setting the guide of a rip saw machine to rip stock in widths corresponding to multiples of a selected unit of measurement, for instance, one eighth of an inch.

Another object is to provide mechanism of the character and for the purpose above set forth, adapted for attachment to the usual type of rip, or edging machine saws, without necessitating modification of the latter.

Other and subordinate objects are also comprehended by my invention, all of which, together with the exact nature of my improvements, and the advantages thereof, will be readily understood when the following description and claims are read with reference to the drawings accompanying and forming part of this specification.

In said drawings:

Figure 1 is a view in top plan illustrating my improved setting mechanism applied to a straight line rip, or edging machine saw.

Figure 2 is a view in front elevation.

Figure 3 is a view in end elevation of a combined detent and gauge bar forming part of my invention, together with a supporting bracket therefor.

Figure 4 is a fragmentary view partly in transverse section and partly in side elevation, taken on the line 4—4 of Figure 1, looking in the direction indicated by the arrows.

Figure 5 is a detail view in transverse section taken on the line 5—5 of Figure 4 looking in the direction indicated by the arrows.

Figure 6 is a fragmentary view in perspective of a trigger bar forming part of my improved setting mechanism.

Figure 7 is a view in bottom plan of a detent member, and

Figure 8 is a detail view in vertical transverse section, partly in elevation, taken on the line 8—8 of Figure 1, looking in the direction indicated by the arrows.

Referring to the drawings by numerals, the illustrated embodiment of my invention has been shown as applied to a well known type of rip or edging machine saw including the usual table 1 across which the stock is fed, in a well known manner, beneath the usual head 2, by means of a travelling bed represented at 3, past the rip saw, or saws, for cutting the stock along a line indicated by a well known form of line indicator 4. In the type of machine with which my inven-

tion is particularly concerned, the stock is fed past, and against, a stock guide, or "fence" 5 which is suitably mounted on the front edge of the table 1 for adjustment along the same laterally of the stock, to gauge the width to be cut 5 from the latter.

According to my invention, means are provided for adjusting the guide 5 as follows:

Pivoted on the table 1, as by the pivot bolt 6, to extend forwardly of said table, 10 is a horizontally swingable bar-like hand lever 7 provided at its front end with an upstanding handgrip 8. The hand lever 7 is operatively connected to the guide 5 by means of a link 9 pivoted at one end to the guide 5, as at 10, and having its opposite end similarly secured to the hand lever 7 intermediate the ends of the latter as at 11. The handgrip end of the hand lever 7 extends over and forwardly of a horizontally disposed combined gauge and detent bar 12 of arcuate 20 form and fixed to the table 1 to extend forwardly thereof for movement of said end of the lever 7 thereover. As will be understood, said bar 12 is curved concentrically of the axis of movement of the hand lever 7. Preferably one end of the 25 bar 12 has extending therefrom an integral bracket arm 13 by means of which said bar is bolted, as at 13', to one end of the table 1.

The opposite end of the bar 12 is secured to the underside of the table 1 by means of a substantially U-shaped bracket 15 depending from said bar and bolted thereto as at 16 and to the table 1 as at 17. The bracket 15 is of the described shape to clear the front edge of the table 1 as will be understood. The bar 12 is provided with 35 an upper toothed edge 18, the teeth being of ratchet form and spaced, in the present instance, a quarter of an inch apart.

Mounted on the hand lever 7 for vertical rocking movement to engage and disengage the teeth 40 18 is a detent member 19 of right angled form including a horizontal plate 20 disposed in the engaged position of said member flat on the hand lever 7, and having along one edge thereof a depending bevelled flange 21 forming a dog for 45 engagement with the teeth 18. The mounting for the detent member 19 comprises a right angled bracket 22 underlying the hand lever 7, and comprising a pair of long upstanding arms 23 extending above said lever at one side thereof and a pair 50 of shorter upstanding arms 24 terminating flush with the upper face of said lever. A pair of bolts 25 are extended upwardly through slots 26 in the bracket 22 into the lever 7 and a pair of set screws 27 are similarly disposed in the short arms 55

24 of the bracket 22 for engagement with the adjacent side of the hand lever, whereby said bracket is adjustable transversely of the hand lever 7. The end of the plate 20 opposite to the flange 21, is pivotally mounted between the long arms 23 of the brackets 22 by means of a pivot bolt 28. As will be seen by adjusting the bracket 22 the detent member 19 may be similarly adjusted to properly locate the flange 21 in the teeth 18 of the combined detent and gauge bar 12.

5 Slidably mounted on the hand lever 7, for end-wise movement longitudinally thereof, is a trigger bar 29 extending through a pair of guides 30 bolted to said arm 7 upon opposite sides of the 10 detent member 19, respectively, as at 31 and 32, and extending through a groove 33 formed in the underface of the detent member 19. The trigger bar 29 is provided at its front end with an up-standing finger grip 34 located adjacent to the 15 handgrip 8 to be conveniently grasped by the fingers of the hand of an operator grasping said handgrip, whereby the trigger bar 29 may be moved forwardly of the hand lever 7. A tension spring 35 having one end secured to a stud 36 20 on said trigger bar 29 and its other end secured to a stud 37 on the hand lever 7, urges the trigger bar 29 rearwardly into normal position. The normal position of the trigger bar 29 is established by means of a bolt 38 extending upwardly through 25 the hand lever 7 to be engaged by the rear end of the trigger bar 29. Secured to the underside of the hand lever 7, as by the bolt 38 and a nut 39 threaded onto the stud 37, is a guide arm 40 underlying the combined detent and gauge bar 35 12 to prevent upward movement of the hand lever 7.

In the normal position of the trigger bar 29, the detent member 19 lies flat against the hand lever 7 with the bevelled flange 21 engaged with 40 the teeth 18 of the combined detent and gauge bar 12, said member being gravity actuated into engaging position.

The trigger bar 29 is designed, upon forward movement thereof from normal position, to move 45 the detent member 19 to disengaging position and for this purpose is provided with an upper cam face 41 co-acting with a similar face 42 formed in the groove 33 to lift said detent member 19 into a position in which the flange 21 is clear of the teeth 18. Co-acting devices are provided 50 on the hand lever 7 and trigger bar 29 for releasably locking the trigger bar against return from its forward position in which the detent member 19 is disengaged, thereby releasably locking said member 19 against movement into engaging 55 position relative to the teeth 18. In this instance, such means comprises a cam stud 43 extending upwardly from the upper face of the hand lever 7 and seating, with a snap action, in 60 a notch 44 in the underface of the trigger arm 29 adjacent the front end thereof, it being understood that the trigger arm 29 is sufficiently resilient to permit the front end thereof to ride up over the cam stud 43. As will be understood, by upward 65 lifting of the front end of the trigger bar 29, through the medium of the finger grip 34, the notch 44 may be disengaged from the stud 43, or vice versa, whereby the trigger bar, when released, will snap back into normal position releasing the detent member 19 for gravitational 70 movement into engaging position relative to a subjacent tooth 18 of said bar 12.

As will now be seen, by swinging of the hand lever 7 in opposite directions, the stock guide 5 75 may be moved toward and from the stock, respec-

tively, to gauge the thickness of the cut from the stock and the hand lever 7, together with the guide 5, set in a selected position by coaction of the detent member 19 with the teeth 18 of said bar 12. In this connection, and for obvious reasons, the teeth 18 and flange 21 are designed for coaction to lock the hand lever and guide 5 against movement outwardly of the stock, or, saw line, and to permit said detent member 19 to ratchet over said teeth 18 upon movement of said lever 7 and guide 5 in the opposite direction. The link 9 is connected to the hand lever 7 to effect one-eighth inch increments of movement of the guide 5 for each tooth 18 past which the flange 21 is moved. In other words, the hand lever 7 is moved in quarter inch increments and the guide 5 in eighth increments of movement. The purpose of this is to enable the operator to cut strips in widths corresponding to multiples of an eighth of an inch for each one-fourth inch of movement of the hand lever 7, this being the unit of measurement most commonly used in cutting strips in certain lines of work, for instance, in veneer work. The face of the combined detent and gauge bar 12 is numbered, as at 20 46, with numbers up to 20 at every fourth tooth 18 for accurate setting of the hand lever 7 in inch increments of movement. Slidably and removably mounted on said bar 12 is an auxiliary stop 25 47 settable along said bar and having a tooth 48 for engagement with a selected tooth 18 to retain the same in set position. The stop 47 is for blocking movement of the hand lever 7 past a predetermined setting as will be clear.

35 The operation of my invention will, it is believed, be clear from the foregoing without further explanation.

While in the foregoing I have described certain preferred relations and constructions of parts, it 40 is to be understood that the present disclosure is illustrative rather than restrictive and that modifications both in relation of parts and details of construction may be resorted to without departing from the inventive concept. Hence right is 45 herein reserved to all such modifications falling within the scope of the claims appended hereto.

What I claim is:

1. In a rip saw machine, including a stock supporting table, and a stock guide laterally settable 50 in opposite directions, guide setting means including a hand lever pivoted at one end on the table for horizontal swinging movement and operatively connected to said guide, said lever having a hand grip end, a toothed arcuate detent 55 bar mounted on said table for swinging movement of said lever thereover, a detent dog comprising an arm overlying said lever transversely and a right angled tooth-engaging end depending therefrom along-side said lever, said arm being pivotally mounted on said lever to engage said end with said toothed bar by gravity, means for elevating said arm and thus disengaging said end from the toothed bar comprising a bar-like trigger member slidably mounted on top of said 60 lever for movement along the same toward and from said hand grip end thereof, respectively, and having a hand grip adjacent the hand grip end of the lever, said trigger member extending underneath the arm of said dog and having an 65 upper cam face coacting with said arm to elevate the latter upon movement of said trigger member in one direction, and means tensioning said trigger member against movement in said 70 one direction.

2. In a rip saw machine, including a stock supporting table, and a stock guide laterally set-table in opposite directions, guide setting means including a hand lever pivoted at one end on the table for horizontal swinging movement and operatively connected to said guide, said lever having a hand grip end, a toothed arcuate detent bar mounted on said table for swinging movement of said lever thereover, a detent dog comprising an arm overlying said lever transversely and a right angled tooth-engaging end depending therefrom alongside said lever, said arm being pivotally mounted on said lever to engage said end with said toothed bar by gravity, means for elevating said arm and thus disengaging said end from the toothed bar comprising a bar-like trigger mem- ber slidably mounted on top of said lever for movement along the same toward and from said hand grip end thereof, respectively, and having a hand grip adjacent the hand grip end of the lever, said trigger member extending underneath the arm of said dog and having an upper cam face coacting with said arm to elevate the latter upon movement of said trigger member in one direction, means tensioning said trigger member against movement in said one direction, said trigger member being resilient, and a pair of devices on said lever and member, respectively, coacting with a snap action under reaction of said trigger member to lock the latter against movement under the urge of said tensioning means. 15

ROBERT W. STEWART.
